EYEGLASS FRAME FRONT

William E. Woodruff, 245 Jackson St.,
Columbus, Ohio 43206

Filed June 8, 1970, Ser. No. 23,342

Term of patent 14 years

Int. Cl. D16—06

U.S. Cl. D57—1

FIG. 1

FIG. 2

FIG. 3

FIG. 1 is a perspective view of an eyeglass frame front showing my new design;

FIG. 2 is a front elevational view;

FIG. 3 is a side elevational view thereof;

FIG. 4 is a front elevational view of a modified eyeglass frame front showing my new design;

FIG. 5 is a side elevational view of the modified eyeglass frame front of FIG. 4;

FIG. 6 is a front elevational view of another modified eyeglass frame front showing my new design;

FIG. 7 is a side elevational view of the eyeglass frame front of FIG. 6;

FIG. 8 is a front elevational view of another modified eyeglass frame front showing my new design; and

FIG. 9 is a side elevational view of the eyeglass frame front of FIG. 8;

The broken lines appearing in FIGS. 1, 3, 5, 7, and 9 are intended to illustrate environmental structure which forms no part of the present design.

I claim:

The ornamental design for an eyeglass frame front, substantially as shown and described.
